UNITED STATES PATENT OFFICE.

RICHARD GREENLEAF TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-REPLENISHING MECHANISM FOR DOUBLE-SHUTTLE LOOMS.

Application filed January 5, 1926. Serial No. 79,479.

This invention relates to improvements in bobbin changing double shuttle looms of the type used to weave double fabrics and it is the general object of the invention to provide 5 a loom of this type with a magazine the bobbins of which move to transfer position by gravity.

In looms of the type specified the lay is provided with a pair of shuttle boxes at each end 10 to receive two shuttles one moving through the upper shed and the other moving through the lower shed. Both shuttles lay filling each pick of the loom and said shuttles may move in opposite directions or may be moved in 15 the same direction. It has been proposed heretofore to provide looms of this type with magazines in which the bobbins are positively moved to transfer position but such a magazine entails the use of chains or other 20 actuated means operative to move the bobbins after each transfer and they have usually been of the type which required that the bobbins move to transfer position in pairs so that if but one of a pair of bobbins is transferred the other untransferred bobbin of the 25 pair must move out of position and a fresh pair moved into transfer position. It is an important object of my present invention to provide a magazine wherein the bobbins move 30 to transfer position by gravity, the bobbins not necessarily moving in pairs but being able to adapt themselves to the conditions of transfer so that if but one shuttle is replenished there will not necessarily be a corresponding movement on the part of the bobbin 35 positioned for the other shuttle.

It is a further object of my invention to make the distance between the axes of the shuttles a multiple of the diameter of the 40 bobbin so that when the latter fall to position they will be properly placed for transfer.

It is a still further object of my invention to provide the transerrer arms with supporting wings which support the bobbins above the arms during the transferring operation to the end that the bobbins next above the arms may not be positioned to prevent withdrawal of the transerrer arms.

With these and other objects in view which will appear as the description proceeds, my invention resides in the combination and arrangement of parts hereinafter described and set forth in the claims.

In the accompanying drawings wherein one 55 convenient embodiment of my invention is shown,

Fig. 1 is a front elevation of a portion of a double shuttle loom having my invention applied thereto,

Fig. 2 is a vertical section on line 2—2 of Fig. 1 on an enlarged scale,

Fig. 3 is a horizontal section on line 3—3 of Fig. 2,

Figs. 4 and 5 are views similar to Fig. 2 65 but showing the transerrer arms in different positions,

Fig. 6 is a vertical section on line 6—6 of Fig. 2 on an enlarged scale,

Fig. 7 is a vertical section on line 7—7 of 70 Fig. 3,

Fig. 8 is an enlarged horizontal section on line 8—8 of Fig. 1, and

Fig. 9 is a vertical enlarged section on line 9—9 of Fig. 1.

Referring to the drawings it will be seen that I have provided a loom frame 10 in which is mounted for reciprocating movement a lay 11 having located at the right hand end thereof as shown in Fig. 1 upper and lower shuttle boxes 12 and 13 respectively, each provided with a feeler slot 14 for the reception of any approved form of weft detector such for instance as that contemplated in Patent No. 1,150,448. The opposite or left hand end of the lay is provided with upper and lower shuttle boxes 15 and 16, respectively, the rear walls of which are slotted as at 17 for the passage of exhausted bobbins. Each of said boxes 15 and 16 is provided with a binder 18 slotted to permit the passage of a full bobbin and said boxes receive shuttles S and S' having bobbins B and B'. It is to be understood that the shuttles move back and forth through the sheds of the 85 loom as the lay reciprocates.

Located in front of the shuttle boxes 15 and 16 is a magazine M having outer and inner vertical guides 20 and 21, respectively, each slotted to receive the tips and butts, respectively, of a stack of bobbins W as shown in Figs. 7 and 8. The rear wall of guide 20 has formed therein upper and lower openings 22 and 23, respectively, each of which receives a yielding gate 24 which moves inwardly about a vertical pin 25 and is held normally in the position shown in Fig. 3 by means of torsion spring 26. Between the openings 22

and 23 there is located a stop 27 integral with the guide 20 and positioned to prevent horizontal motion of the next to the bottom bobbin of the magazine.

- 5 As shown in Fig. 8 the rear wall of guide 21 is provided with upper and lower openings 28 and 29, respectively, each adapted to receive a gate 30 similar to gate 24 in construction and operation. Formed in-
10 tegral with the guide 21 is a stop 31 in substantial horizontal alignment with and serving the same purpose as the stop 27. The bobbins W have their tips and butts in the guides 20 and 21, respectively, and it will be seen
15 by referring to Figs. 3 and 5 that the lowest and second from the lowest bobbins are in such position that they can be moved horizontally against the yielding action of the gates 24 and 30.
- 20 In order to impart horizontal motion to the bobbins in transfer position I provide a transfer mechanism comprising a stud 32 fixed to the loom frame and having pivotally mounted thereon a pair of transfer levers
25 33 and 34 which cooperate with the upper and lower shuttles, respectively. Said transferrer levers are provided with cup shaped bobbin engaging heads which are of substantial length as shown in Fig. 3 and
30 35 extend parallel to the bobbins. In Figs. 3 and 4 it will also be seen that the transferrer levers are provided with forwardly extending fingers 35 which extend forwardly far enough to support the bobbins thereover
35 when the transferrer arms are in their rear-most position.

As seen in Fig. 2 said transferrer levers 33 and 34 are provided with depending legs 36 and 37, respectively, of unequal length.
40 Pivots mounted at the bottom of the legs 36 and 37 are transferrer latches 38 and 39, respectively, which are positioned for engagement with bunters 40 and 41, respectively, mounted on and moving with the lay 11.
45 Extending downwardly from the under side of the magazine frame is a bracket 42 in which are slidably mounted cam blocks 43 and 44, respectively, controlled as to longitudinal position by means of rods 45 and 46, respectively. Said rods extend to the opposite side of the loom and may be controlled by weft detectors in the manner set forth in the aforesaid patent. Each of said blocks is provided with a cam face 47 which is formed as one wall of a notch formed in the under side of the blocks. Each transferrer latch is provided with a forwardly extending tail 48 which normally occupies a notch in one of the blocks. As shown in Fig. 6 the trans-
50 ferrer levers have hubs 49 around which lie coil springs 50 connected to the levers and the bracket 42 to hold the said levers yieldingly in the position shown in Fig. 5.

Under normal conditions the bobbins and the transferrer levers are in the position in-

dicated in Fig. 5 and the lay will move forwardly to the position indicated in said figure until a change of weft is necessary, at which time one or the other of the aforesaid rods will be moved. In Figs. 1 and 6 it is 70 assumed that the rod 45 has been moved to the right so that the corresponding block 43 is also moved to the right causing a depression of tail 48 of the latch 38 because of the action of cam 47 on block 43. The latch 38 75 is thus raised into the position shown in Fig. 2 and as the lay advances the bunter 40 will engage said latch 38 and swing the trans- ferrer lever 33 rearwardly as shown in Fig. 2. This action on the part of lever 33 causes 80 the second from the bottom bobbin to move against the gates 24 and 30 into the shuttle S at the same time expelling bobbin B which has become exhausted and which gave the indication for transfer. As the lever 33 85 moves rearwardly the third from the bottom bobbin will rest on the fingers 35 thus supporting all bobbins above said lever 33 to prevent the same from falling or assuming a tilted position in the magazine. As the lay 90 moves backwardly the lever 33 will be re- turned by its spring 50.

In Fig. 4 it is assumed that two transfers are occurring simultaneously in which instance both the blocks 43 and 44 will be 95 moved to the right and both the latches 38 and 39 will be raised so that the transferrer levers will both be given a transferring movement to the rear. It will be seen that the next to the bottom bobbin lies between the transferrer levers and as lever 34 moves forwardly said bobbin will fall to the lowest position and upon the next operation of lever 34 will be moved into the shuttle S'. 100

The blocks 43 and 44 are returned to normal position after engagement of the bobbins with the latches by mechanism not set forth herein but well understood and contemplated in the aforesaid patent. 105

It will be seen by referring to Figs. 2, 4, 110 and 5 that the distance between the axes of the shuttles is twice the diameter of the bobbin and that the bobbin above the bottom bobbin is opposite the stops 27 and 31 so that even though the bobbins on both sides thereof are being transferred as indicated in Fig. 4 115 said bobbin will not be moved toward the shuttles.

From the foregoing it will be seen that I have provided a magazine for a double shuttle loom wherein the bobbins are moved by gravity to proper position for transfer and that their diameter is such with respect to the distance between the axes of the shuttles that the bottom and second from the bottom bobbins will always be positioned in registry with the lower and upper shuttles, respectively. It will also be seen that it is not necessary to provide mechanism for positively moving the bobbins and that the latter are 120 125 130

held against improper angular position in the magazines by the fingers extending forwardly from the heads of the transfer levers. It will also be seen that the next to the 5 bottom bobbin is restrained positively against horizontal motion when the bobbins on either side thereof are being transferred.

Having thus described my invention it will be apparent that changes and modifications 10 may be made therein without departing from the spirit and scope of the invention, and I do not wish to be limited to the details herein disclosed, but what I claim is:

1. In a weft replenishing loom having two 15 shuttle boxes in vertical alignment to receive shuttles having slots extending horizontally therethrough, a magazine to receive a stack of bobbins which are moved by gravity to a plurality of transfer positions, the upper 20 bobbin in transfer position being supported by the lower bobbin which is in transfer position, the distance between the centers of the shuttles when in transfer position being a multiple of the diameter of the bobbins in 25 the magazine, each bobbin moving in a substantially horizontal direction from the magazine into the respective shuttle.

2. In a weft replenishing loom having two 30 shuttle boxes in vertical alignment to receive shuttles having slots extending horizontally therethrough, a magazine to receive a stack of bobbins which are moved by gravity to a plurality of transfer positions which are equidistant from the shuttles at the time of 35 transfer, the two bobbins in transfer position being separated by a third bobbin, said third bobbin and the upper bobbin deriving their support from the bottom bobbin, said third bobbin remaining untransferred 40 when the bottom bobbin and the bobbin above said third bobbin are transferred.

3. In a weft replenishing loom having two 45 shuttle boxes in vertical alignment to receive shuttles having slots extending substantially horizontally therethrough, a magazine to receive a stack of bobbins which are moved by gravity to a plurality of transfer positions which are equidistant from the shuttle boxes when the latter are in a position for transfer- 50 ring, the two bobbins in transfer position being separated by a third bobbin and the upper bobbin in transfer position being supported by the third bobbin, said third bobbin remaining untransferred when either the 55 lower or the upper bobbin in transfer position is transferred into a corresponding shuttle.

4. In a weft replenishing loom having two 60 shuttle boxes in vertical alignment to receive shuttles having slots extending substantially horizontally therethrough, a magazine to receive a stack of bobbins which are moved by gravity to a plurality of transfer positions which are equidistant from the shuttle boxes 65 when the latter are in a position for transfer-

ring, the two bobbins in transfer position being separated by a third bobbin and the upper bobbin in transfer position being supported by the third bobbin, said third bobbin remaining untransferred when either the 70 lower or the upper bobbin in transfer position is transferred into a corresponding shuttle, the distance between the shuttles when in transfer position being equal to the distance between the upper and lower bobbins which 75 are in transfer position.

5. In a weft replenishing loom having two 80 shuttle boxes in vertical alignment to receive shuttles having slots extending substantially horizontally therethrough, a magazine to receive a stack of bobbins which are moved by gravity to a plurality of transfer positions which are equidistant from the shuttle boxes when the latter are in a position for transferring, all the bobbins of the magazine above the 85 lowest deriving their support from the lowest bobbin, the distance between the centers of the shuttles when in transfer position being a multiple of the distance between the centers of adjacent bobbins in the magazines, the 90 second bobbin above the bottom bobbin being in transfer position and being held in said position by the bobbin immediately above the lowest bobbin, the bobbins when being transferred moving in substantially horizontal di- 95 rections.

6. In a weft replenishing loom having two 100 shuttle boxes in vertical alignment to receive shuttles having slots extending substantially horizontally therethrough, a magazine to receive a stack of bobbins which are moved by gravity to a plurality of transfer positions which are equidistant from the shuttle boxes when the latter are in a position for transferring, said magazine to hold three bobbins 105 in vertical alignment, the upper and lower of which are in transfer position and the intermediate bobbin of which rests on the lowest bobbin and in turn supports the upper bobbin, and means to transfer the upper and lower bobbins in a substantially horizontal 110 direction into the corresponding shuttles while the intermediate bobbin remains untransferred.

7. In a weft replenishing loom having two 115 shuttle boxes in vertical alignment to receive shuttles having slots extending horizontally therethrough, a magazine to receive a stack of bobbins which are moved by gravity to a plurality of transfer positions which are 120 equidistant from the shuttles at the time of transfer, the two bobbins in transfer position being separated by a third bobbin, said third bobbin and the upper bobbin deriving their support from the bottom bobbin, said 125 third bobbin remaining untransferred when the bottom bobbin and the bobbin above said third bobbin are transferred, the distance between the shuttles when in transfer position being a multiple of the distance between 130

adjacent bobbins in the magazine and said bobbins being movable in a substantially horizontal direction when being transferred from the magazine into the corresponding shuttles.

5. 8. In a weft replenishing loom having two aligned shuttle boxes to receive shuttles, a magazine to receive a series of aligned bobbins which move by gravity and in contact with each other to a position substantially 10 parallel to the shuttles when the latter are in transferring position, the distance between the centers of the shuttles when in transfer position being a multiple of the diameter of the bobbins in the magazine, each bobbin 15 when moving into the corresponding shuttle moving in a direction which is substantially perpendicular to the line joining the centers of the shuttles.

9. In a weft replenishing loom having two 20 shuttle boxes in vertical alignment to receive shuttles having slots extending horizontally therethrough, a magazine to guide bobbins which are moved by gravity in contact with each other to a plurality of transfer 25 positions so that the bobbins in transfer position shall be at the same distance from

their corresponding shuttles, and means to transfer a bobbin from either transfer position into the corresponding shuttle in a substantially horizontal direction, the distance 30 between the centers of the shuttles when in transfer position being a multiple of the diameter of the bobbins in the magazine.

10. In a weft replenishing loom having two shuttle boxes in vertical alignment to receive shuttles having slots extending horizontally therethrough, a magazine to receive a plurality of bobbins each movable by gravity in contact with each other to one or the other of two transfer positions, the upper 40 bobbin in transfer position being supported by the lower bobbin which is in transfer position, the bobbins when in the transfer positions being spaced apart a distance equal to the distance between the shuttles when the 45 latter are boxed, each bobbin moving in a substantially horizontal direction from the magazine into the respective shuttle.

In testimony whereof I have hereunto affixed my signature.

RICHARD GREENLEAF TURNER.
